DESIGN FOR A COMBINED AQUARIUM, CLOCK, AND VASE

Leopold Weiss, New York, N. Y.

Application November 14, 1934, Serial No. 54,009

Term of patent 3½ years

To all whom it may concern:

Be it known that I, Leopold Weiss, a citizen of Germany and a resident of New York, in the county of New York, in the State of New York, have invented a new, original, and ornamental Design for a Combined Aquarium, Clock, and Vase, of which the following is a specification, reference being had to the accompanying drawing, forming a part thereof.

Fig. 1 is a plan view of the article with the

chains, vase and support therefor omitted, and Fig. 2 is a front view of the same, showing my design.

I claim:

The ornamental design for a combined aquarium, clock, and vase as shown.

Signed at New York, N. Y., this 7 day of November, 1934.

LEOPOLD WEISS.
